US00D861093S

(12) **United States Design Patent** (10) Patent No.: **US D861,093 S**
(45) Date of Patent: ** Sep. 24, 2019

(54) **GOLF CLUB HEAD**(71) Applicant: **KARSTEN MANUFACTURING CORPORATION**, Phoenix, AZ (US)(72) Inventors: **Cory S. Bacon**, Cave Creek, AZ (US);
Daniel K. Lee, Chandler, AZ (US);
Xiaojian Chen, Phoenix, AZ (US)(73) Assignee: **Karsten Manufacturing Corporation**,
Phoenix, AZ (US)(**) Term: **15 Years**(21) Appl. No.: **29/656,488**(22) Filed: **Jul. 12, 2018**(51) LOC (12) Cl. **21-02**

(52) U.S. Cl.
